PARQUET FLOOR BLOCK

Harold P. Schuck, Shamrock, Fla.

Application January 23, 1933, Serial No. 653,133

5 Claims. (Cl. 20—8)

This invention is intended to provide a novel parquet floor block or composite section having certain decided advantages constituting an improvement upon my prior Patent No. 1,510,924 dated October 7, 1924, and other articles of the kind.

Its object is to produce a block of the greatest possible strength in a very simple and light construction, adapted or applicable to the various 10 purposes and ways of laying for or in which other blocks of a similar character are designed and employed. Comparative inexpense with a minimum of labor in manufacture are additional desiderata of importance in this connection.

15 The invention will be best understood by further description with reference to the attached drawing illustrating a practicable embodiment thereof in several different forms of incidental distinction.

20 In said drawing:

Fig. 1 is a perspective view of the basic block member;

Fig. 2 is a corresponding view of the member in one complete form with connecting elements 25 at the sides;

Fig. 3 is a like view of the member in another complete form;

Fig. 4 similarly represents the member in a further complete form;

30 Fig. 5 correspondingly illustrates still another complete form of the member; and

Fig. 6 represents a cross-sectional view of the member taken on the line 6—6 of Fig. 4.

The illustrative block, denoted as a whole by 7, 35 comprises a plurality of ordinary wooden floor pieces 8 of equal length, arranged longitudinally abreast or edge to edge with the usual tongue and groove formations along their edges fitted together as represented in the cross-sectional view 40 of Fig. 6. These pieces advantageously have also the usual "hollow back" grooving in their bottoms as shown, for greater facility in laying in cement to a sub-floor or to otherwise provide for ventilation therebelow. Although such pieces are preferred, it is not essential that such shall be used, 45 inasmuch as substantially the same results can be obtained with plain strip material flat on all sides. Neither is it necessary for the pieces to be of wood, since some other material such as, 50 composition fibre or the like may in certain cases be preferred.

At opposite ends of the pieces lying thus together, grooves or kerfs 9 are formed in their edges as shown clearly in Fig. 1. It is desirable for 55 these grooves to be of a liberal depth for purposes which will appear, and it is proposed to make them approximately one and a half inches deep in a block of the ordinary size, which is 9 x 9 inches. As the size of the block may vary 60 according to preference and design however, there

is no fixed depth for the grooves which need only be suitably proportional to the size of the block for the intended purpose.

Into the bottoms of these end grooves, uniting 65 splines 10 of wood or other material are pressed so as to lie transversely of the pieces in what may be called a "countersunk" position. In such position they do not fully occupy or close the grooves and so leave them outwardly open. If the splines are three quarters of an inch wide as ordinarily 70 preferred, the remaining parts of the grooves will of course be of corresponding measure in depth. Said splines serve not only to bind and hold the pieces together in a rigid block structure due to the compression therewithin, but also to strengthen 75 the pieces in such union, and located as they are deep within the ends of the pieces they perform these functions on lines disposed inwardly toward the transverse center of the block so as to render it far stronger than the ordinary block 80 having end inserts.

The block formed in this way is adapted to end-to-end interconnection with other blocks by reason of the open grooves at its ends, but is of course unadapted to such connection with others 85 at its sides because there is no grooving or tenoning thereat. Accordingly, in this form it is suitable only for sectional laying in strip fashion or relation after the manner of ordinary hardwood flooring. But said block constitutes the basic 90 member from which other forms complete and adapted to laying in parquet relation are made.

One of these complete forms is represented in Fig. 2. This comprises the basic block having 95 grooves 11 formed in opposite sides thereof to a depth corresponding to that at which the grooves 9 in the ends are left after application of the uniting splines. In this form of the block, loose splines 12 providing interchangeable tongues are adapted to be applied to said grooves at the sides as indicated, so as to connect the section with others similarly formed. These loose splines or tongues may of course be applied in the grooves at the ends as well as the sides of the block whenever it should be necessary for connection with other sections, said tongues being intended to be applied anywhere or to any of the grooves with equal facility. So applied, they of course project outwardly like a tenon and fit into corresponding grooves of the adjacently placed sections. It will be noted that the ends of the countersunk splines are trimmed off somewhat by the cutting of the grooves in the sides of the block, but this will not be sufficient to materially affect or reduce their strengthening properties and the width and length thereof are such as to adequately serve that purpose if shortened even more.

Another form of the block is illustrated in Fig.

3. In this, tongues instead of grooves are formed 115 at opposite sides. Such tongues are in this in- 120

stance integral with the block, comprising portions 13 of the outermost pieces of the same, together with the end portions of the uniting splines (10). In other words, the tongues are formed in three parts 10—13—10. This is attained simply by passing the basic block between coacting saws set to trim the outermost pieces into said tongue formations, the same being of course on a level with the grooves in the ends. In so forming the tongues, the saws merely cut away edge portions of the outermost pieces without cutting away the uniting splines and so provide the tongues in said three parts 10—13—10. It should be stated in this connection that when tongues are to be thus formed on the blocks, it is preferable to have the outermost pieces of a wider width than the others in the initial assembly, so that after the cutting away in tongue formation, they will superficially appear to be of the same width as the intermediate pieces. This tongue formation has an advantage over the ordinary integral tongue of block members in that the ends of the uniting splines (10) forming extremal continuations thereof add greatly to their strength and rigidity, eliminating the possibility of any splitting or breaking away from the block. So rigid are the tongues so formed that it is impossible to knock them off or pry them loose by attempted leverage within the groove of another section. A material improvement accordingly resides in this feature apart from others characterizing this invention.

Fig. 4 represents a further complete form of the block, in which are combined features of those of Figs. 2 and 3. In other words, in this particular form the block is provided with a groove 11 in one side and an integral tongue 10—13—10 on the opposite side. Into said groove 12 is of course adapted to fit for connection with an adjacent section, while the integral tongue will fit in the groove of another adjacent section. The two grooves at the ends are of course intended to receive either the integral tongue or the loose tongue of corresponding sections. This form accordingly embodies certain advantages of both the prior described forms and so may be laid in various ways, including reversal.

Fig. 5 illustrates a still further form of the block embodying a modification of the previous one. In this, a groove 11 is formed in one side and an integral tongue 10—13—10 on the other side the same as the previous form, but instead of a loose tongue applied in said side groove, the tongue 12 is fitted into one of the end grooves, and if so desired may be frictionally or adhesively affixed therein so as to be virtually integral with the block. This provides a block having a tongue on one side and end and a groove in the other side and end. It has certain advantages and desirability in laying into a floor construction, although it is not considered superior to any of the other forms, each of which will produce a floor of the same appearance and durable quality.

It will be noted that in all of the illustrated forms of the block, the uniting splines countersunk in the grooves at the ends terminate flush or substantially flush with the side edges of the block at the same level. In other words, the ends of the splines lie flush with said edges whether tongues or grooves are formed at the sides. If a groove is formed in the side, its end is flush with the bottom edge of the groove and if a tongue is formed on the side, its end is flush with the outer edge of the tongue.

A novel and improved floor block of extremely strong, simple and light construction is accordingly provided, which is adapted or applicable to the various purposes and laying methods of other blocks. It has the advantage of comparative inexpensive in manufacture due to the minimum amount of workmanship required and the elimination of any special part or different material for uniting the pieces together. The uniting splines are simply pressed into countersunk position within the end grooves while the component pieces are held under lateral compression and this may be done very speedily and expeditiously by machine so as to manufacture the blocks in quantities far exceeding the possibility of others requiring special workmanship or treatment. The invention accordingly makes a valuable contribution to the art as an improvement over the ordinary floor block or section.

Having thus described my invention, what I claim as new and desire to secure by Letters Patent of the United States is:

1. A floor block comprising a plurality of flooring pieces arranged longitudinally abreast, uniting splines countersunk in squeezing fit into transverse grooves in the edges of the pieces at opposite ends thereof so as to rigidly bind the pieces together on lines inwardly spaced from such ends and still leave said grooves outwardly open, and a tongue formed along the side edge of an outermost of the pieces; said tongue having its ends composed of extremities of said splines in the transverse grooves.

2. A floor block comprising a plurality of flooring pieces arranged longitudinally abreast, uniting splines countersunk in squeezing fit into transverse grooves in the edges of the pieces at opposite ends thereof so as to rigidly bind the pieces together on lines inwardly spaced from such ends and still leave said grooves outwardly open, and a tongue formed along the side edges of an outermost of the pieces; said tongue being in three parts with its intermediate portion integral with such piece and its ends composed of extremities of said splines.

3. A floor block comprising two or more pieces united together and provided with tongues on opposite edges, the two other edges being grooved and provided with splines uniting said pieces in a squeezing fit, and extending beyond the pieces to form the extremities of the tongues.

4. A floor block comprising a plurality of wooden pieces arranged longitudinally abreast and having a tongue in one side edge, said tongue having an intermediate part with a grain running substantially parallel to said pieces and end parts with grain running cross-wise thereto; the cross-wise grain parts being formed by wooden splines inserted in grooves in the end edges of the block and uniting the several pieces together in a squeezing fit within said grooves leaving the latter open to engage the tongues of other blocks.

5. A floor block comprising a plurality of flooring pieces arranged together longitudinally abreast and formed with a tongue on one side edge and with a groove on the other side edge; its edges at opposite ends being grooved and provided with transverse splines countersunk in said grooved edges in a squeezing fit uniting the pieces together and extending flush with the tongue on the one side edge and with the bottom of the groove on the other side edge of the block.

HAROLD P. SCHUCK.
